UNITED STATES PATENT OFFICE.

JOHN MERRY, OF NEW YORK, N. Y., ASSIGNOR TO THE BIGELOW CARPET COMPANY, OF MASSACHUSETTS.

DESIGN FOR A RUG.

SPECIFICATION forming part of Design No. 30,828, dated May 16, 1899.

Application filed April 18, 1899. Serial No. 713,517. Term of patent 3½ years.

To all whom it may concern:

Be it known that I, JOHN MERRY, a subject of the Queen of Great Britain, and a resident of the city, county, and State of New York, have invented a new and useful Design for Rugs, of which the following is a specification.

My design, as shown in the drawing, consists in a new design for a rug.

10 The design is composed of a middle portion and a border.

The middle portion is bounded by a stripe, which also constitutes the inner margin of the border and forms a rectangle containing a bold ornamental central figure of rectangular shape. Ornamental figures triangular in 15 shape and connected together in a row form on each of the four sides of the rectangle a continuous decorated border for the same.

20 The balance of the rectangle is profusely ornamented with small geometrical figures of conventional rug-pattern.

The border is composed of a main broad inner stripe and a narrower outer stripe, on

each side of both of which are less conspicuous narrow stripes. The main stripe of the border is profusely ornamented with bold 25 oriental rug-like figuring of conventional flower, leaf, and spray design, intermingled with medallion, shield-like, and arabesque 30 decorations. The other stripes are profusely ornamented with less conspicuous shapes suggestive of oriental-rug decorations.

The drawing shows one-quarter of the design. The remaining three-quarters are in 35 all respects facsimiles of it.

What I claim, and desire to secure by Letters Patent, is—

The design for a rug substantially as shown and described.

In testimony whereof I have signed my name to this specification in the presence of two subscribing witnesses.

JOHN MERRY.
